US00D766767S

(12) **United States Design Patent** (10) **Patent No.:** **US D766,767 S**
(45) **Date of Patent:** **** Sep. 20, 2016**

(54) **ELECTRONIC DEVICE**

(71) Applicant: **Garmin Switzerland GmbH**,
Schaffhausen (CH)

(72) Inventors: **Marcos J. Bowman**, Overland Park,
KS (US); **Juhee Lee**, Olathe, KS (US);
Nicholas B. Greusel, Overland Park,
KS (US)

(73) Assignee: **Garmin Switzerland GmbH** (CH)

(**) Term: **15 Years**

(21) Appl. No.: **29/528,135**

(22) Filed: **May 26, 2015**

(51) LOC (10) Cl. **10-07**

(52) U.S. Cl. **D10/128**
USPC ....

(57) **CLAIM**

The ornamental design for an electronic device, as shown and described.

DESCRIPTION

FIG. 1 is a front perspective view of an electronic device according to embodiments of the present invention;

FIG. 2 is a rear perspective view of the electronic device;

FIG. 3 is a top view of the electronic device;

FIG. 4 is a front view of the electronic device;

FIG. 5 is a bottom view of the electronic device;

FIG. 6 is a rear view of the electronic device;

FIG. 7 is a left side view of the electronic device; and,

FIG. 8 is a right side view of the electronic device.

The broken lines shown in FIGS. 1 through 8 represent portions of the electronic device that form no part of the claimed design.

1 Claim, 3 Drawing Sheets
